(57) **CLAIM**

The ornamental design for a deodorizing assembly, as shown and described.

DESCRIPTION

FIG. 1 is an upper perspective view of a deodorizing assembly mounted on a toilet according to an embodiment of the invention.

FIG. 2 is an upper perspective view of the deodorizing assembly of FIG. 1.

FIG. 3 is a front view of the deodorizing assembly of FIG. 1.

FIG. 4 is a back view of the deodorizing assembly of FIG. 1.

FIG. 5 is a right side view of the deodorizing assembly of FIG. 1.

FIG. 6 is a left side view of the deodorizing assembly of FIG. 1.

FIG. 7 is a top view of the deodorizing assembly of FIG. 1; and,

FIG. 8 is a bottom view of the deodorizing assembly of FIG. 1.

The broken lines showing of a toilet in FIG. 1 are included for the purpose of illustrating environment and forms no part of the claimed design. Other broken lines showing structural elements in FIGS. 1-5, 7, and 8 form no part of the claimed design.
